DESIGN FOR A FAUCET OR SIMILAR ARTICLE

Walt W. Cushman, Webb City, Mo.

Application February 17, 1947, Serial No. 136,963

Term of patent 3½ years

(Cl. D91—3)

To all whom it may concern:

Be it known that I, Walt W. Cushman, a citizen of the United States and residing at Webb City, in the county of Jasper and State of Missouri, have invented a new, original, and ornamental Design for a Faucet or Similar Article, of which the following is a specification, reference being had to the accompanying drawings, forming a part thereof.

Fig. 1 is a plan view of a faucet or similar article, showing my new design.

Fig. 2 is a side view of the same.

Fig. 3 is a front view of the same.

Fig. 4 is a bottom view of the same.

Fig. 5 is a perspective view of the same.

The dominant features of my design reside in the portions shown in full lines.

I claim:

The ornamental design for a faucet or similar article, as shown and described.

WALT W. CUSHMAN.
